UNITED STATES PATENT OFFICE.

CARL F. BUSCHNER, OF NEW YORK, N. Y.

DESIGN FOR A TASSEL FOR TRIMMING.

SPECIFICATION forming part of Design No. 13,866, dated April 24, 1883.
Application filed March 14, 1883. Term of patent 3½ years.

To all whom it may concern:

Be it known that I, CARL F. BUSCHNER, of the city of New York, in the county and State of New York, have invented a new and original Design for a Tassel for Trimming, of which the following is a specification, reference being had to the accompanying drawings, forming part thereof.

Figure 1 is a side view of my newly-designed tassel, and Fig. 2 a vertical central section of the same.

Similar letters of reference indicate corresponding parts in both figures.

This invention relates to a new and original design for a tassel, A, for trimming.

The tassel is of tapering form, and is composed of three sections, *a b c*, of tufted or plush-like fabric, divided by two buttons, *d* and *e*. The button *d* is larger than the button *e*. In

the tufted sections *a b c* the tassel is composed of radiating silk or other threads, as shown. These threads, or some of them, may, if desired, be left uncut at the ends, as indicated in the sections *b* and *c*. The buttons *d e* are shown to be ornamented by radial chains or cords *f*. The tassel ends in a ball, *g*.

I claim as my invention—

1. The design for a tassel, consisting of the buttons *d e*, between the sections *a b c*, of tufted fabric, the tassel being of tapering form, substantially as shown.

2. The design for a tassel, consisting of buttons *d e*, between tufted sections *a b c*, and of the ball *g*, substantially as shown.

CARL F. BUSCHNER.
